UNITED STATES PATENT OFFICE.

THOMAS C. SPELLING, OF NEW YORK, N. Y.

PRINTING PRESS.

Application filed March 16, 1927. Serial No. 175,891.

This invention relates to certain new and useful improvements in letter printing presses and deals particularly with that type of apparatus which is used for producing so-called "form letters."

Usually letters of this character are first printed upon a press or multigraph machine, leaving the addressee's space blank. This blank space is afterwards filled in on a typewriter and usually the type of the typewriter machine is of a different character or of a different impression than that of the body form of the letter. In other instances slugs carrying a type impress of the name, address and salutation are used. In either case the letter, as a whole, is given unsightly form which is quickly noticeable by the differentiating features as to the filled-in part of the letter over that of the printed form.

It is therefore the principal object of the present invention to overcome these difficulties by producing a machine wherein a little chase containing type identical with that set up in the letter chase is fed into its proper position at the head of the body of the letter so that the name of the addressee, his address and the proper salutatory are printed simultaneously with that of the set up form. The type employed in the little chase corresponds with that in the letter form, hereinafter designated as the letter chase. By giving the letter made up in this fashion a simultaneous impression, the whole letter will have a uniform appearance. It is notable that full advantage is here taken for the first time of the fact that type foundries now manufacture and sell what is known as standardized typewriting type.

Another object of the invention is the provision of a machine in which the little chases are successively fed into position at the head of the set up form letter.

Another object of the invention resides in the novel manner in which little chases are fed from a galley into their proper position at the head of the form letter.

In still another instance, an attempt was made to make the bodies of letters on a plurality of mechanically operated typewriters and then insert the name, etc. with the same kind of hand operated typewriter. But it was found that the difference between results of impressions were clearly apparent upon casual inspection.

Other objects and aims of the invention, more or less broad than those stated above, to-

gether with the advantages inherent, will be in part obvious and in part specifically referred to in the course of the following description of the elements, combinations, arrangement of parts and application of principles constituting the invention, and the scope of protection contemplated will appear from the appended claims.

In the accompanying drawings, which form a part of this specification, similar figures of reference indicate like parts throughout the several views in which:

Fig. 1 is a sectional side view of the invention, taken through the galley, slot and press bed, midway between the parts of the letter type chase, exhibiting assembled parts of the invention.

Fig. 2 is a detached perspective view of the inclined galley seen in Fig. 1, exhibiting its parts, the spring 23 shown broken off in order to exhibit the opening 25.

Fig. 3 is a bottom view in perspective of one of the little chases.

Fig. 4 is a top view of one of the little chases and equipment.

Fig. 5 is a detached view of a member attached to the inclined galley, as seen in Fig. 1, its use being thereafter explained.

Fig. 6 is a view of the letter chase, i. e. an oblique bottom view of parts 12 and 13, showing protuberances at corners for fastening the letter chase.

The mechanical result sought is to displace a little chase containing type matter for the name, address and proper salutatory of one individual, firm or corporation with another little chase containing those of another, which takes the former's place at each completed movement of the press.

It will be noted that the letter chase consists of two separate parts, one part on either side of a passage-way for the little chases, the passage way hereinafter referred to as the slot, 11. In the narrower of the two parts, designated, 12, will be set the type for printing the part of a letter commonly known as the caption or letterhead, in any proper type, and under it, properly related, the date, the latter to be set in the same style of type as the body of the letter. The other part of the letter chase, 13, carries the type for the body, or text, of the letter. Of course, even the signature may be printed if a suitable cut be provided.

In hereinafter referring to the "letter chase," the term is to be understood to include both the parts, 12 and 13. These parts may

be suitably fastened to the floor of the press, 29, but, as constructed, and as designed solely for printing on a press the floor of which is horizontally positioned, their weight is sufficient to hold them securely in position. Slight downward protuberances, 31, at the corners to occupy spaces made for them in the press floor provides ample fastening means. The space between them, as positioned for press impression, is of sufficient width to allow the passage between them of the little chase, 14. The thickness of the bases of members, 12 and 13, is exactly the same as that of the ungrooved portions of the little chases, 14. It will be noted that the slot, 11, extends less than one half the width of the letter chase, and terminates at the margin of an opening through the press floor. Suitably attached at the inner margin of this opening, to the nether surface 20 of the press floor, is the slanted chute 15, in which each ejected little chase slides before falling to the floor of the press room, or into a container, the purpose of providing the slanted chute, 15, being the breaking of the 25 force of the fall of the little chase and prevention of resulting injury to the type carried therein. In practice, it is necessary to construct the containing walls of the letter chase adjacent to this opening thinner than the 30 portions thereof adjacent to the integral section of the slot, so that the little chases may freely fall through the opening. Hence the shoulders, 16, indicate an exterior diminution of the thickness of the walls. To have the 35 opening also longer than the integral base of the slots presents no problem.

The power of gravity combined with mechanical force is utilized in the invention, and, for its utilization, the inclined galley 32 illustrated in Fig. 2, formed from metal or other suitable material, is employed, both as a feeder and to impart gravity power. As will be noted, it is formed with a slight dip, or curve, near its lower end, that being necessary in order to avoid an angle or acute turn, at the lower end, with resultant clogging or other interference with free movement. The lower end merges into an exactly horizontal section, the horizontal portion being approximately the length of a little chase. The upper surface of the floor of the horizontal portion coincides with the upper surface of the adjacent integral floor of the press. This horizontal portion of the galley is positioned in space made for it by an indentation or channel formed in the substance of the floor of the press at 17. This indentation or channel is suitably formed to securely retain the end of the galley.

In order to make clear the purposes of the openings through the base of the galley it is necessary to include in its further description a description also of the little chase, (Figs. 3 and 4) and of the member illustrated in Fig. 65. 5. The latter, in attachment to the spring 23

performs the important functions of arresting the advance of the file of little chases as they descend through the galley and of allowing the one in the slot to momentarily rest while receiving the print impression, and then 70 immediately releasing the descending file, so that the one just printed is automatically expelled and its immediate successor shoved into the slot to be likewise printed and then expelled, these movements resulting from 75 manipulation of the device by the operator as hereinafter described. This member may be a wire of resilient metal. Its upper end is suitably attached to the base of the galley, and it extends through the staples, 19, to the 80 juncture of the curved and horizontal portions of the galley. At that point is attached to the base of the galley the member, 20. That is a strip, 21, preferably of metal supported on the galley at 22. The spring 85 portion of this member, 23, extends obliquely and terminates in point 24. This point normally extends slightly above the frontal base of any little chase that may be positioned above in operating the device, through the 90 opening, 25. The lower end of the wire, 18, is positioned around the stool, 26, whose bifurcated lower portions straddle the spring, 21. The extreme lower terminal of the wire is suitably connected with the spring, just behind the pointed terminal of the latter as shown in Figure 1. Near the upper attachment to the galley of the wire is attached to the wire the button, 27, which when the parts are at rest, extends upwardly through an 100 opening through the base of the galley, as seen in Fig. 1. Its use will be presently explained.

The little chase, (Figs. 3 and 4) except for the modification of its base is merely a lidless 105 box. Its exterior width is such that it fits snugly, but not tightly, inside the walls of the galley, the space between these corresponding exactly with the width of the slot, 11. Its dimensions are sufficient to allow 110 to be set up therein the type for name, address and suitable salutatory to suit each particular case, and the use of necessary quads, spacers, etc. To very tightly confine the type, thin rubber, leather or other pliable strips, 29^a, 115 are inserted between the type body and the inside surfaces of the sides and ends. These are suitably made fast to the sides and ends and made effective in use by forcing thin spacers between them and the body of type 120 after it is set.

In order that the arresting point, 24, of the wire may not interfere with the free forward movement of the little chase in front of which it was positioned prior to being pulled down, 125 also in order that the contact surface of the little chases may be reduced to a minimum and friction of contact with the bottom of the galley dispensed with, so far as possible, the exterior bases of the little chases are exten- 130

sively grooved, as seen in Fig. 3, and the parts left with which said arresting point, 24 contacts is fractionally shortened, so that in their movements they do not touch the floor of the 5 galley, and thus the necessary length, as well as the steepness of the inclined galley will be considerably abbreviated and limited. And in order that adequate space be left for the free functioning of point 24 between the ends 10 of chases, the corners, 30, of the front ends of the little chases are so formed as to extend forward fractionally.

We now recur to the wire, and strip members above described. In Fig. 1, we observe 15 the point, 24, in position at rest, holding back the file of little chases in the galley. Now the instant that the press impression is made on a completely made up letter, the operator of this machine, seated or standing on a table or plat- 20 form suitable for being stood or sat on, and positioned below the free end of the galley, pushes down the button 27. See Fig. 1 where the position of the table is indicated by the reference numeral 33. That act, by reason 25 of the connection and action of the parts already described, pulls the arresting point, 24 out of position in front of the little chase; and it automatically is sprung back into the groove or channel, 28, upon release of the but- 30 ton. The file of little chases now move ahead, the one in front pushing out that in the slot. But the advancing movement is instantly ar- 35 rested when the front end of the next little chase comes against point 24, now sprung back to normal position. Any alert and healthy man, woman, boy or girl, can keep the galley fed at the top and attend to the button, though new stacks of little chases may have 40 to be arranged on the platform above the table from time to time. An experienced operator should easily feed an automatically (paper) feed and delivery press operating horizontal- 45 ly and running at or near highest speed.

The method of operation is practically cov- 45 ered in what precedes. The preparation for using the invention consists in setting type in both parts of the letter chase and position- 50 ing the latter on the press floor. Setting and securing the type in all the little chases to be used in the customers' list of names and ad- 55 dresses, whether comprising hundreds or thousands is the next preparatory step. (No alphabetical order or classification is here needed.) Then a little chase is placed in the 60 slot and others behind it. And of course the first of the others will rest against point 24, until the galley is full to the top. Now all is 65 ready to start the printing. If the dimensions of the floor of the press warrant it, a plurality 70 of these devices may be used, and the letters for a plurality of lists printed on one press simultaneously. In use, the invention will by no means be limited to letters. It will be 75 equally available in any case where varying 80 data is required to be inserted in a large num- 85

ber of prints which are otherwise the same. And in such uses any suitable type may be utilized. The mechanism and operation of presses whose beds are moved back and forth horizontally are matters too well known to 70 those skilled in the art to require description or illustration.

What I seek to secure by United States Letters patent is:

1. Feeding means for printing presses, 75 comprising a galley adapted to occupy an in- clined position, the interior of the galley being formed to receive and guide a plurality of chases disposed edge to edge therein, a stop mounted on the galley adapted to be pro- 80 jected into the path of the lowermost chase to retard the movement of the chases, said stop being of a character to be spring-actuated, and means for withdrawing said stop com- 85 prising a wire anchored at one end to the galley and connected at its opposite end to the stop, and a device for deflecting the wire and thereby to withdraw the stop.

2. Feeding means for printing presses com- 90 prising a galley adapted to occupy an inclined position, the interior of the galley being formed to receive and guide a plurality of chases disposed edge to edge therein, a stop adapted to be projected into the path of the lowermost chase to retard the movement of 95 the chases, said stop being of a character to be normally thrust into stopping position in the galley, and means for withdrawing said stop comprising a connecting member anchored at one end and operatively connected at its 100 opposite end to control the stop, and means for deflecting said connecting member and thereby to withdraw the stop.

3. In a printing press, the combination 105 with a main chase formed to provide an open- ended space for the reception of a smaller chase, of a plurality of said smaller chases, and means for facilitating the feeding of a smaller chase into cooperative relationship 110 with the main chase including an inclined galley having its discharge end aligned with and in substantially the plane of the main chase, through which the smaller chases may feed in line into the said open-ended space, a 115 stop arranged to engage the lowermost smaller chase for retarding the movement of the smaller chases through the galley, and means for controlling the action of the stop.

4. In a printing press, the combination with 120 a main chase formed to provide an open-ended space for the reception of a smaller chase, of a plurality of said smaller chases, and means for facilitating the feeding and guiding of a smaller chase into cooperative relationship 125 with the main chase including a galley having its discharge end aligned with and in substantially the plane of the main chase, through which the smaller chases may be fed in line into the said open-ended space.

5. In a printing press, the combination 130

with a main chase formed to provide an open-ended space for the reception of a smaller chase, of a plurality of said smaller chases, and means for facilitating the feeding and guiding of a smaller chase into cooperative relationship with the main chase including a galley having its discharge end aligned with and in substantially the plane of the main chase, through which the smaller chases may be fed in line into the said open-ended space, the open-ended space being of approximately the width of the smaller chases in the operative position thereof in the main chase, but of a greater width therebeyond to permit release of the smaller chases through the main chase.

6. In a printing press, the combination with a main chase formed to provide a space for the reception of a smaller chase, of a press floor for supporting the same, a plurality of said smaller chases, and means for facilitating feeding and guiding a smaller chase into cooperative relationship with the main chase by seating the smaller chase in said opening of the main chase, the main chase being provided with depending protuberances adapted to engage the said floor of the press to hold the same against lateral displacement.

7. Feeding means for printing presses comprising a galley, the interior of the galley being formed to receive and guide a plurality of chases disposed edge to edge therein, in combination with said chases having depending supporting edge flanges adapted to ride on the bottom of the galley, and a stop mounted on the galley for retarding the movement of the chases therethrough, said stop being adapted to engage an end portion of the galley when retarding the movement of the chases and to permit the movement of the grooved portion of the chase between said side flanges to ride over the stop when the chase is being shifted.

8. Feeding means for printing presses comprising a galley, the interior of the galley being formed to receive and guide a plurality of chases disposed edge to edge therein, in combination with said chases having depending supporting edge flanges adapted to ride on the bottom of the galley, and a stop mounted on the galley for retarding the movement of the chases therethrough, said stop being adapted to engage an end portion of the galley when retarding the movement of the chases and to permit the movement of the grooved portion of the chase between said side flanges to ride over the stop when the chase is being shifted, the stop-engageable end portion of the chase comprising a depending flange disposed transversely of said grooved portion.

9. Feeding means for printing presses comprising a galley, the interior of the galley being formed to receive and guide a plurality of chases disposed edge to edge therein, in

combination with said chases having depending supporting edge flanges adapted to ride on the bottom of the galley, and a stop mounted on the galley for retarding the movement of the chases therethrough, said stop being 70 adapted to engage an end portion of the galley when retarding the movement of the chases and to permit the movement of the grooved portion of the chase between said side flanges to ride over the stop when the 75 chase is being shifted, the stop-engageable end portion of the chase comprising a depending flange disposed transversely of said grooved portion, said flange being of less depth than the side flanges to be free of contact with the base of the galley.

10. In a printing press, the combination with a main chase formed to provide an open-ended space for the reception of a smaller chase, of a plurality of said smaller chases, 85 and means for facilitating the feeding of a smaller chase into cooperative relationship with the main chase including an inclined galley having its discharge end aligned with and in substantially the plane of the main chase, through which the smaller chases may feed in line into the said open-ended space, and a stop adapted to project through the bottom of the galley to engage the lowermost chase, substantially as described. 95

11. In a printing press, the combination with a main chase formed to provide an open-ended space for the reception of a smaller chase, of a plurality of said smaller chases, and means for facilitating the feeding of a smaller chase into cooperative relationship with the main chase including an inclined galley having its discharge end aligned with and in substantially the plane of the main chase, through which the smaller chases may feed in line into the said open-ended space, and a stop to engage the lowermost chase, the chases having projecting end portions at least at one side thereof to insure spaces being left between adjacent chases for the reception of 100 the stop.

12. Feeding mechanism for printing presses comprising a galley, a plurality of chases disposed edge to edge therein, the chases having a projecting end portion to insure the leaving of a space between adjacent chases, and a stop mounted on the galley adapted to engage the lowermost chase by projecting into the space between the same and the immediately discharged chase. 115

13. A feeding unit for printing presses comprising an inclined galley adapted to receive and guide a plurality of chases, a stop mounted on the galley adapted to be projected into the path of the lowermost chase to retard the movement of the chases by gravity through the galley, and means carried by the galley for withdrawing said stop. 125

14. A feeding unit for printing presses comprising an inclined galley adapted to re- 130

ceive and guide a plurality of chases, a stop mounted on the galley adapted to be projected into the path of the lowermost chase to retard the movement of the chases by gravity 5 through the galley, and means carried by the galley for withdrawing said stop, said means having a manually operable device to control the actuation of the stop.

15. A feeding unit for printing presses comprising an inclined galley adapted to receive and guide a plurality of chases, a stop mounted on the galley adapted to be projected into the path of the lowermost chase to retard the movement of the chases by gravity 10 through the galley, and means carried by the galley for withdrawing said stop, said means having a manually operable

device to control the actuation of the stop, said last mentioned means including a push button and connections from the same to the stop whereby depression of the push button 20 will detract the stop from its retarding position.

16. A gravity force manually controlled feeding unit for printing presses comprising 25 an inclined galley down which chases may feed, means for stopping the movement of the chases through the galley when the latter is in operative position, and hand operative means for the stopping means whereby the 30 discharge of the chases is at the will of the operator.

THOMAS C. SPELLING.
